CAROLINE A. IRMINGER, OF HOBOKEN, NEW JERSEY

THEATER CHAIR LIGHT

Application filed July 24, 1931. Serial No. 552,887.

The objects of the present invention are to provide a reading light for theater chairs, which will enable the occupants of the various seats to individually read their programs without disturbing other patrons, which can be built into or combined in the structure of the chair, so as not to interfere with the use or mar the appearance, which will be of simple, inexpensive construction and protected against breakage or injury.

The foregoing and other desirable objects are attained in this invention by the novel features of construction, combinations and relations of parts hereinafter described and broadly claimed.

The drawing accompanying and forming part of this specification illustrates one simple practical embodiment of the invention, but it will become clear from an understanding of the invention, that the structure may be variously modified and changed without departure from the true spirit and broad scope of the invention.

Fig. 1 is a front elevation of adjoining theater chairs having the invention incorporated therein; Fig. 2 is an enlarged side elevation and broken sectional view showing the light and switch structure in its combined relation with the arm rest of the chair; Fig. 3 is a front elevation of the parts shown in Fig. 2; Fig. 4 is a broken sectional detail of the switch mechanism.

In Fig. 1, adjoining theater chairs of typical design are indicated at 5. Such chairs are usually provided with arm rests 6, which as a rule, project forward to some extent from the metallic side frames 7 of the chairs as indicated particularly in Fig. 2. This projecting arm rest portion is utilized in this invention both as a support and as a guard or protection for the light and the light is made up as a special unit applicable to or combined with such arm rest.

In the form of the invention shown, the light mechanism is a separate unit attachable as such to the underside of the projecting portion of the arm rest. For such purposes, said unit is made up as a casing 8, containing all the necessary electrical parts and attachable as by screws 9 to the flat underside

of the projecting portion of the arm rest. This casing, as shown, is preferably rounded at its forward side, so as to constitute in effect a downward continuation or extension of the rounded forward end of the arm rest 55 and it may be ornamentally or otherwise shaped to accord with the outline of the chair, or decorations in the theater, etc. Preferably, it is of an unobtrusive nature of no greater width than the chair arm and 60 rounded off so as not to catch in clothing or be in the way.

Within the casing or shell of the device, there is mounted a socket 10 to hold a lamp 11 of any usual or special design and a normally open circuit switch having an exposed push button or similar actuating device 12.

In the illustration, the push button of the switch is shown set substantially flush in the front wall of the light casing, so as not 70 to stand in the way, but to be readily accessible to the occupants of adjoining seats. This makes it feasible to provide a light only on every alternate arm rest and for the 75 occupants of the adjoining seats to share the use of the light between them.

The switch is illustrated as of the quick make-and-break spring toggle type, comprising a rocking circuit closing contact member 13, adapted to be snapped in opposite 80 directions past a dead center by a spring 14 and arranged in the one position indicated in Fig. 4, to close the lamp circuit across the contacts 15, 16. It will be noted that the switch will remain in this circuit closed condition only so long as held depressed by the finger, because of the presence of a spring 17, operating on the plunger 18 of the push button to thrust the same outwardly. This plunger has a lost motion connection 19 85 with the rocking element of the switch to initiate the movement of this switch element and at the same time, permit the toggle spring to snap the switch into the open and closed circuit positions.

A reflector or reflecting surface 20 may be disposed in back of the lamp, so as to direct the light downwardly and forwardly, out in the aisle in front of the seat and the light opening 21 in the front of the casing may 90

be covered by a lens or glass 22. This latter structure may be in the form of a hinged door 23 releasably secured by a lock or latch 24, permitting access by authorized persons 5 for replacement of lamps or other service requirements.

In this invention, the lighting mechanism is combined with the chair structure in an out of the way position but in such a relation 10 that it is favorably disposed to direct the light forwardly and downwardly from the chair, where it will illuminate a program held by the occupant of the chair without annoying adjoining or nearby patrons 15 and where it may be usefully employed to locate lost articles dropped in the aisle or by ushers in directing or seating patrons. If desired, the lighting unit may be built into or constructed as an original part of the arm 20 rest, instead of as an attachment afterwards applied. The necessary wiring may be in the form of armored cable, indicated at 25 and carried from the back of the casing to suitable conduits extended along a row of 25 chairs, or, for instance, set in the floor, the methods of wiring depending largely upon whether the lights are installed initially or put in subsequently after the original building operations. It is the intent of the 30 invention however, that available lighting current be employed, all the seat lights having a common source, as distinguished from systems employing individual batteries for the different lights and which are known to be 35 unsuitable because of the uncertainty of dry cells, etc. A special feature to be noted is that the push button, located as it is in the hand supporting portion of the arm rest, is conveniently situated for hand actuation 40 and at the same time, is not so exposed as to be in the way or to catch in the clothing. The lighting units being mounted on stationary parts of the chairs and being disposed 45 in the spaces between adjoining chairs, do not in any way interfere with the normal and proper use of the chairs, are not in the way and do not take up any otherwise useful space. The push buttons may be located in 50 special positions on the floor or on the chair structure, so as to be operable by foot pressure, instead of by hand. In either case, they are constructed so as to snap the light off as soon as the actuating pressure is removed, thus insuring that the lights will 55 remain on only so long as they are actually being used. By being directed forwardly, the lights will serve to illuminate not only the aisle in front of a row of chairs, but the 60 spaces beneath the chairs in the row ahead, a convenience in finding articles dropped under the chairs.

As the invention is of broad scope, the terms employed herein are to be considered 55 in a descriptive rather than in a limiting

sense, except possibly for limitations as may be imposed by the state of the prior art.

What is claimed is:

1. In combination with a row of theater chairs having arm rests, light units carried by the alternate arm rests and consisting of individual switch controlled electric lights attached to the arm rests in a manner so as to direct illumination downwardly and forwardly from said arm rests towards the aisle 75 in front of said chairs.

2. In combination with a row of theater chairs having arm rests, light units carried by the alternate arm rests and consisting of individual switch controlled electric lights attached to the arm rests in a manner so as to direct illumination downwardly and forwardly from said arm rests towards the aisle 80 in front of said chairs and wiring for carrying lighting current from a common source 85 to said alternately disposed lighting units on said arm rests.

3. In combination with a row of theater chairs having arm rests, program reading light units carried by alternate arm rests and comprising each a casing attached to and forming in effect an extension of the arm rest, said casing having a light opening therein, a transparent cover over said light opening, a lamp mounted in the casing, a reflecting surface back of said lamp, said light opening, lamp and reflecting surface being positioned to direct illumination below, forward and away from the arm rest to enable convenient reading of a program by a seated patron, a switch connected to control said lamp and mounted in the casing at one side of the lamp, said switch having a control button exposed at one side of the casing and current carrying wiring extending to the switch and lamp 100 of each lighting unit.

In testimony whereof I affix my signature.
CAROLINE A. IRMINGER.
